UNITED STATES PATENT OFFICE.

FREDERICK A. SCHOSOW, OF DETROIT, MICHIGAN.

FLUSHING-VALVE.

1,368,764.

Specification of Letters Patent. Patented Feb. 15, 1921.

Application filed April 7, 1919. Serial No. 287,969.

To all whom it may concern:

Be it known that I, FREDERICK A. SCHOSOW, citizen of the United States, residing at Detroit, county of Wayne, State of Michigan, have invented a certain new and useful Improvement in Flushing-Valves, and declare the following to be a full, clear, and exact description of the same, such as will enable others skilled in the art to which it pertains to make and use the same, reference being had to the accompanying drawings, which form a part of this specification.

My invention relates to flushing valves shown in the accompanying drawings and more particularly pointed out in the following specification and claims.

One object of the invention is to provide a simple and effective device in which the usual rubber ball valve is eliminated.

Another object of the invention is to provide a construction whereby the valve is held to its seat through the action of a float until manually raised, whereupon the float serves to maintain the valve off its seat, until the altitude of the water in the tank is insufficient to further affect the action of the float.

With the foregoing and other objects in view which will appear as the description proceeds, the invention resides in the combination and arrangement of parts and in the details of construction hereinafter described and claimed, it being understood that changes may be made in the precise embodiment of the invention herein disclosed without departing from the spirit of the same.

In the accompanying drawings forming part of this specification:—

Figure 1 is a longitudinal vertical sectional view through the device, showing a fragment of a flushing tank, with the flushing valve seated.

Fig. 2 is a similar view showing the flushing valve raised, and the inlet valve or ball cock open.

Fig. 3 is a detail view of the operating lever, with parts in section.

Fig. 4 is a plan view of the flushing valve and operating mechanism.

Fig. 5 is a detail view—partly in section—of the rocker arm with which the ball float and flush valve are connected.

Referring now to the letters of reference placed upon the drawings:—

A, denotes the flushing tank. B, the inlet

valve or ball cock. C, indicates the flushing valve proper. D, is the casing of the flushing valve and D' is its seat. C', is a valve stem for guiding the valve to its seat. F, denotes an overflow pipe opening into the casing of the valve D through a hole projection D² extending laterally from the valve casing, said laterally directed hole projection D² having a portion D³ extending into the valve casing D and provided with an aperture D⁴ through which the stem C' operates to guide the valve C to its seat D'.

G, is a bracket secured to the upper end of the overflow pipe in which is journaled a rock shaft H. I, denotes a link connecting one arm of the rock shaft with the manually operated lever J, supported in the wall of the flushing tank. K, indicates a link connection between the flush valve C, and another arm of the rock shaft H. L, is a ball float provided with an adjustable rod M, pivoted to still another arm of the rock shaft H. N, indicates an adjustable screw for regulating the tilting action of the rock shaft H. O, is a turn buckle for adjusting the length of the rod M. P, is a guide for the rod M, supported upon the overflow pipe.

Having indicated the several parts by reference letters, the construction and operation of the device will be readily understood.

When the flushing valve C, is seated and the tank is full of water, as indicated in Fig. 1 of the drawings, the upward thrust of the ball float L,—due to its buoyancy—will through the rod M, acting upon the rock shaft H, and the link connection with the flush valve, serve to maintain the latter upon its seat until manually raised through the operation of the lever J.

The lever J, having been operated, the flush valve is thereby lifted from its seat due to the link connection between it and the rock shaft H. The rocking shaft H, having now assumed the position indicated in Fig. 2 of the drawings, the upward thrust of the ball float—due to its buoyancy—acting upon the rock shaft, will maintain the flush valve in its "raised" position until the level of water in the tank has been reduced to a point where the buoyancy of the float is no longer effective to support the valve, whereupon it will drop to its seat by gravity, thereby permitting the tank to again fill with water. By adjusting the screw N, the rocking action of the shaft

H may be controlled, that it may always be in position for effective operation.

Having thus described my invention, what I claim is:—

- 5 1. In a device of the character described, a tank, a flushing valve, an over-flow pipe, a bracket secured to the upper end of the over-flow pipe and projecting laterally therefrom, a rock shaft mounted in the outer 40 end of the bracket and thereby spaced from the over-flow pipe and provided with arms, an operating lever, a link between the operating lever and one of the arms of the rock shaft, a float member connected to another 45 of the arms of the rock shaft, and a link connection between a third arm of the rock shaft and said valve.
- 10 2. In a device of the class described, a tank, a flushing valve, an over-flow pipe arranged vertically in the tank and having 50 communication with the flushing valve, a bracket secured to the upper end of the over-flow pipe and projecting horizontally therefrom, a rock shaft mounted in the outer 55 end of the bracket and provided with arms, an operating lever, a connection between the operating lever and the rock shaft, a float member in the tank having connection with an arm of the rock shaft, and a link 60 connection between another arm of the rock shaft and said valve.
- 15 3. In a device of the character described, a tank, a flushing valve in the tank, an over-flow pipe in the tank, a bracket secured to 65 the over-flow pipe, a rock shaft mounted

in the bracket, an operating lever, a connection between the operating lever and said rock shaft, a float member in said tank including an arm having connection with said rock shaft, means whereby the length of said rod may be adjusted, a guide mounted on the over-flow pipe for the guidance of said rod, and a link connection between said valve and the rock shaft.

4. In a device of the character described, 45 a tank, a rock shaft having angularly related arms, a flush valve suspended from one of the arms of the rock shaft, means for guiding the flushing valve to its seat, a float having a suspension rod connected with the 50 other of said arms of the rock shaft, a guide eye for the float rod, the arm of the rock shaft connected with the float being movable to a position at one side of the line joining the pivot and float for forming a lock 55 to hold the float against upward movement and the valve on its seat, and movable to another position at the opposite side of the said line to release the float and permit the same to support the valve in an open position while the entire flushing water is being discharged from the tank, and manually operable means for operating the rock shaft.

In testimony whereof I sign this specification in the presence of two witnesses.

FREDERICK A. SCHLOSSOW.
